UNITED STATES PATENT OFFICE

WALTER H. KNOBLOCH, OF ERIE, PENNSYLVANIA, ASSIGNOR TO ERIE ART METAL COMPANY, OF MILLCREEK TOWNSHIP, ERIE COUNTY, PENNSYLVANIA, A CORPORATION OF PENNSYLVANIA

CORNER STRUCTURE

Application filed July 3, 1928. Serial No. 290,235.

In forming cases having metal faces, such as refrigerator cases, difficulty has been experienced in finishing the corners. This is particularly true where the metal faces of the walls have enamel finish. It is desirable to bevel the edges of the corner strips and where this is done and they are brought up tight against the enamel finish the sharp edges of the strips crack the enamel and further the sheared edges do not make as fine a finish as is desirable. The present invention obviates this difficulty. Features and details of the invention will appear from the specification and claims.

15 A preferred embodiment of the invention is illustrated in the accompanying drawings as follows:—

Fig. 1 shows a perspective view of a portion of a case such as is ordinarily used for refrigerators.

Fig. 2 a front view of a corner of the case, slightly enlarged.

Fig. 3 an enlarged section on the line 3—3 in Fig. 1.

25 1 marks the walls of the case. These are provided with the wall plates 2, which plates are preferably coated with enamel 3. The wall plates are secured on a frame 4 and when used for refrigeration insulating material 5 is provided within the wall plates and a lining 5^a within the insulating material.

Corner strips 6 are arranged along each of the corners, these corner strips being of angle form in cross section and overlapping adjoining plates 2. These angle strips have the beveled edges 7 which seat at 8 upon the side plates 2. A fold 9 is formed in the extreme edges of the plates, these folds being folded down closely on the beveled portion 7. The 35 folded edge 10 forms a seating surface at 8 and the exposed edge of the strip is nicely rounded by the fold.

The corner strips are provided with countersunk openings 11, the beveled edges lifting the strips sufficiently from the plates 2 to afford clearance for the countersunk portion and screws 12 pass through these openings into the wall securing the corner strips in place.

50 Corner pieces 13 are arranged over the

strips 2 and these have the beveled edges 14 provided with a fold similar to the fold 9 and they are secured by screws 15 in the same manner that the strips are secured. The folded edge gives a better finish but where enamel is used it gives sufficient contact surface to prevent the cracking of the enamel.

55 What I claim as new is:—

1. A corner structure comprising wall plates extending from the corner; and a corner strip of angle form in cross section overlapping the wall plates, the strip being folded back upon itself at its edges and the fold edges beveled and seated upon the faces of the wall plates.

60 2. A corner structure comprising wall plates extending from the corner; and a corner strip of angle form in cross section overlapping the wall plates, the strip being folded back upon itself at its edges and the fold edges beveled and seated upon the faces of the wall plates, said corner strips having countersunk openings and screws in the openings.

65 3. A corner structure comprising wall plates extending from the corner, said plates having enamel faces; and a corner strip of angle form in cross section overlapping the wall plates, the strip being folded back upon itself at its edges and the fold edges beveled and seated upon the faces of the wall plates.

70 In testimony whereof I have hereunto set my hand.

75 WALTER H. KNOBLOCH.
